UNITED STATES PATENT OFFICE.

CHARLES L. FORTIER, OF MILWAUKEE, WISCONSIN.

TYPE-WRITING MACHINE.

No. 878,789.

Specification of Letters Patent.

Patented Feb. 11, 1908

Application filed March 26, 1906. Serial No. 307,993.

To all whom it may concern:

Be it known that I, CHARLES L. FORTIER, a citizen of the United States, and a resident of Milwaukee, county of Milwaukee, and 5 State of Wisconsin, have invented certain new and useful Improvements in Type-Writing Machines, of which the following is declared to be a full, clear, and exact description.

10 The invention relates to type-writing machines, particularly to tabulating mechanism therefor.

15 The improvement provides a simple construction for tabulating work without employing the letter-spacing escapement therefor and also provides a light carriage for this work that will start and move quickly but which may be arrested with little shock or jar, without the use of brakes, dash-pots or 20 other retarding devices, to thereby increase the life of the machine and increase the rapidity with which tabulating work may be done.

25 With these and other objects in view the invention consists in the features of construction, combinations and arrangements of parts hereinafter set forth, illustrated in the accompanying drawings and more particularly pointed out in the appended claims.

30 The invention is more particularly adapted for and is shown applied to a machine of the so-called "visible" or "front-strike" type, although it may be readily adapted to other forms.

35 In the drawings Figure 1 is a longitudinal section of the machine to which the present improvements are applied, the section being taken on line 1—1 of Fig. 2. Fig. 2 is a rear view of the machine with certain parts 40 broken away. Fig. 3 is a detail section on the line 3—3 of Fig. 1. Fig. 4 is a detail plan view with certain parts shown in section on line 4—4 of Figs. 1 and 2.

45 The key levers 10 are mounted as usual in horizontal series in the base portion of the machine frame 11. The levers are pivoted at their rear ends upon a common fulcrum ledge 12 and their forward upturned ends are provided with finger pieces or keys 13. 50 Springs 14 normally uphold the key levers against a transverse stop-bar 15. Type-bars 16 (one only of which is shown) are pivoted upon a segment 17 to strike upwardly and rearwardly against the front of the platen 18 and suitable links connect the 55 key-levers and type-bars. The type mech-

anism described may be of any usual or desired construction.

To provide means for tabulating with ease and rapidity and without shock and jar upon the parts of the machine, the paper-holding means or platen is mounted upon a light supplemental carriage which, in turn, is connected to and is preferably mounted to slide upon a main carriage that is provided with 60 one member of the letter spacing escapement and with the other appliances usually mounted upon the tabulating carriage. The main and supplemental carriages are connected and normally shift together for ordinary work, but in tabulating the light supplemental carriage may be released from the main carriage for quick shift to the proper columnar position. Inasmuch as such a supplemental carriage is much lighter than 65 those usually employed, it will have less inertia and may be quickly moved by a comparatively light spring and will be arrested with little shock or jar upon the parts of the machine, and it is not necessary to release 70 the letter-space escapement.

The main and supplemental carriages may be of any suitable or desired construction. In the form shown, the main carriage comprises the front and rear bars 20 and 21 connected by the side bars 23. The rear bar 20 of the main carriage (see Figs. 1 and 2) is provided with downwardly projecting perforated lugs 24 through which extends a guide-bar or rail 25 that is fixed at its ends to a pair 90 of brackets 26 projecting laterally from the upper rear portion of the machine frame. The front bar 21 of the main carriage in the form shown, is provided with a pair of central depending lugs 27 (see Fig. 1) between 95 which is mounted a roller 28 that engages a cross rail 29 on the front of the machine frame. The side bars 23 of the main carriage are provided with depending circular or loop-shaped portions so that they do not interfere with the independent shift of the light supplemental carriage.

100 The supplemental carriage comprises the side bars 30 connected at their rear ends by a longitudinally extending rod 31 and at their forward ends by the platen supporting shaft 32. The bar 31 of the supplemental carriage is provided with depending lugs 33 (see Fig. 3) and preferably adjustably secured thereto by screws 34. The lower ends of the lugs are 105 in the form of perforated ears and engage a rail or guide-rod 35 that is fixed at their op-

posite ends to a lug 36 and to a laterally extending bracket 37 on the side bars 23 of the main carriage. An adjustable stop or collar 38 upon the guide or track-bar 35 of the main carriage is arranged to engage one of the lugs 33 of the supplemental carriage to limit the return movement of the supplemental carriage with reference to the main carriage. The supplemental carriage however, may be moved in letter-space direction independently of the main carriage, and to permit its full shift in such direction, one end of the track or guide-bar 35 is connected to the laterally extending bracket 37 on the main carriage. The supplemental carriage is also provided with a U-shaped frame bar 39 extending beneath the platen and connected at its ends to the side-bars 30. This U-bar is provided with a central roller 40 that engages the track-bar 41 that is vertically shiftable and mounted centrally upon an upright 401. This upright is mounted on its lower ends upon a pair of rock arms 402 that extend forwardly therefrom and are journaled at the forward ends in a bracket 403 depending from the segment 17. The lower arm is mounted on a rock shaft 404 that extends from the side of the machine frame and is provided, preferably at each end, to the rock arm 405 connected by a link 406 to a suitable shift key. By this means the supplemental carriage may be shifted vertically, swinging about the rod 35, for printing "upper case" letters. The longitudinal bars 31 and 39 of the supplemental carriage serve to support the guide plate 42 and other paper-guiding and holding means. A line-space lever 43 is provided with a spring-pawl 44 arranged to engage the teeth of the ratchet 45 on the end of the platen. The construction and arrangement of the main and supplemental carriages may be widely varied, as desired, from that set forth without departure from the essentials of the invention.

A spring-actuated propelling drum 46 of usual construction is mounted on the stud shaft 47 at the back of the machine frame, and is connected by a drive-strap 48 with an arm 49 that is connected to and depends from one of the side bars 30 of the supplemental carriage. This drum may be of sufficient power to propel both carriages, but preferably a second drum 50 mounted on the stud 51 is connected by a strap 52 to an arm 53 connected to and depending from one end of the rear bar 20 of the main carriage.

A suitable letter-space escapement mechanism is arranged to coöperate with the main carriage. In the form shown this mechanism comprises a rack 54 extending between the rear ends of the side bars 23 of the main carriage and a rocker 55 provided with dogs 56 engaging the rack 54. The rocker is mounted upon a bracket 57 fixed to the rear portion of

the machine frame and is connected by a link 65 58 to the universal bar 59 extending beneath the key-levers 10.

The main and supplemental carriages are normally connected by suitable releasable devices for tabulating escapement comprising a rack 60 mounted on one of the carriages and a dog 61 for engaging the rack mounted upon the other carriage. In the form shown, rack 60 is pivoted in upright position upon the rear bar 20 of the main carriage. The pintles of the rack are provided with stop pins 62 for engaging lugs 63 (see Fig. 2) and springs 64 (see Fig. 1) fixed to the side bars of the main carriage normally uphold the rack 60 in vertical position 80 with the stop pin 62 in engagement with the lug 63. The teeth of the rack 60 are beveled and the dog 61 is of a one-way yielding spring-held type so arranged that independent movement of the carriages in letter-space 85 direction is prevented when the rack is in engagement with the dog. But the supplemental carriage may be returned independently of the main carriage as dog 61 will then pass idly over the teeth of the rack 60 until 90 the lug 63 on the supplemental carriage engages the stop or collar 38 on the main carriage.

Suitable means are provided for shifting the rack to disengage it from the dog, such 95 means comprising a shiftable member in the form of a bell lever 65 that is pivoted to the bracket 57 on the rear of the machine casing and projects upwardly through a slot therein. At its upper end the shiftable member 100 65 is provided with a forwardly extending abutment 66 that is arranged to engage rack 60 and shift it against the tension of its spring 64 out of engagement with the dog 61, so as to release the supplemental carriage 105 and permit its free run in letter-space direction under the influence of the propelling drum 46. The shiftable bell lever 65 is actuated by a tabulating key lever 67 mounted within the base portion of the machine 110 frame and pivoted on the fulcrum 12 of the type-bar key-levers. The tabulating key-lever 67 is connected to the bell-lever 65 by a link 68. This key-lever is cut away (see Fig. 1) above the universal bar 59 so that its 115 movement will not operate the letter-space escapement but will serve merely to release the tabulating escapement formed by the rack 60 and dog 61 to permit the free run of the supplemental carriage.

Any suitable form of tabulating mechanism may be employed for arresting the run of the supplemental carriage. In the form shown, the supplemental carriage is provided with a stop supporting bar 69 having a 125 series of openings 70 within which the column-stops 71 may be set or adjusted in any desired position. The stops 71 are prefer-

ably provided with shank portions 72 that fit snugly within the hole 70 to securely hold the stops in place upon the bar 69. Bar 69 is, as shown, arranged above the rack 60 on the main carriage and the dog 61 that engages the rack 60, is conveniently mounted at one end of the stop supporting bar 69, as shown in Fig. 2.

The dog 73 for coöperating with the column-stops, is conveniently mounted on the shifting bell-lever 65 so as to be moved therewith into the path of the column-stops when the tabulating key-lever 67 is depressed. The spring 74 (see Fig. 1) engages the bell-lever 65 and normally holds the dog 73 out of the path of the column-stops 71 and the abutment 66 in such position that the rack 60 of the main carriage may engage the dog 61 on the supplemental carriage.

When the tabulating key-lever is depressed, the rack 60 is disengaged from the dog 61 to permit the free run of the supplemental carriage and at the same time stop-dog 73 is projected into the path of the column-stops 71 so that the supplemental carriage will be arrested in proper columnar position. By reason of the light weight of the supplemental carriage, it will start and move easily and quickly and will be arrested without shock or jar upon the parts of the machine. The life of the machine and the rapidity with which tabulating work may be done is thus materially increased since it is unnecessary to employ brakes, dash-pots or other retarding devices which, although they may check somewhat the shock and jar upon the machine parts, materially decreases the speed at which the tabulating work may be done. Moreover, inasmuch as only the light supplemental carriage is shifted, when tabulating, the propelling drum 46 therefor may be provided with a comparatively light spring. In ordinary work, both carriages will be propelled by the drums 46 and 50 that will have springs of sufficient combined strength for this purpose. It will be noted that the letter-space feed is not released for tabulating work.

To gradually check the movement of the supplemental carriage when released, the stop-dog 73 is preferably pivoted between ears or lugs 75 (see Fig. 2) on the side of the bell-lever 65, and a spring 76 normally holds the main portion of the dog away from the bell-lever but with the tail-portion 77 of the dog in engagement therewith. When one of the column-stops 71 engages the dog 73, it will move it in letter-space direction until the dog is arrested by its engagement with the bell-lever 65. As this movement of the dog is against the tension of the spring 76, the latter will serve to gradually bring the supplemental carriage to rest without shock or jar.

Suitable means are preferably provided to

prevent the rebound of the supplemental carriage when one of the column-stops is brought into engagement with the stop-dog 73. For this purpose, the upper end of the bell-lever 65 is provided with a horizontally disposed pivoted pawl 78 (see Fig. 4) which, when the bell-lever is projected forwardly is arranged to engage inclined ratchet teeth 79 on the lower portion of the rear face of the stop supporting bar 69. This dog and the ratchet teeth are so inclined that the supplemental carriage may freely move in letter-space direction, but any backward movement or rebound after one of the column-stops engages the stop-dog is prevented.

It will be understood that the teeth of the racks 60 and 79 are spaced apart in correspondence with the teeth of the letter-space rack 54, the teeth of the latter of course corresponding with the different letter-space positions of the main carriage, as indicated by the scale or pointer 80 and 81 at the front of the machine.

To securely hold the stop-dog 73 in proper position, the bell-lever that carries the dog is arranged to swing between a pair of lugs 82 and 83 on the back portion of the machine (see Fig. 2). The lug 83 extends upwardly and engages the upper portion of the bell-lever 65 on the side opposite the stop-dog 73, so that the impact of the dog against the bell-lever 65 is taken up by the lug 83.

It will be noted that the rack 54 and the dogs 56 on the rocker 55 form the ordinary letter space escapement, while the rack 60 and dog 61 form a separate, independent tabulating escapement. With the ordinary tabulating devices the free run of the carriage is effected by releasing the letter space escapement. In the present device the letter space escapement is not shifted or released, but the free run of the carriage or paper carrying devices is permitted by releasing the supplemental tabulating escapement that is entirely separate and independent of the letter space escapement.

It is obvious that the details set forth may be widely varied without departure from the essentials of the invention.

Having described my invention, what I claim as new and desire to secure by Letters Patent, is:—

1. In typewriting machines, the combination of a main carriage, a supplemental carriage normally shifting therewith, releasable devices connecting said carriages and tabulating mechanism associated with said supplemental carriage for arresting its run when released from said main carriage.

2. In typewriting machines, the combination with the main and supplemental carriages and propelling means therefor, of releasable devices normally connecting said carriages, tabulating mechanism coöperating with said supplemental carriage to arrest its

run when released from said main carriage and means for operating said releasing devices and tabulating mechanism.

3. In typewriting machines, the combination with the main and supplemental carriages releasably connected to shift together, of tabulating mechanism coöperating with said supplemental carriage to arrest the same when released from said main carriage, said tabulating mechanism comprising a series of column-stops and coöperating dogging means and key mechanism for releasing said supplemental carriage and for projecting one of the members of said tabulating mechanism 15 in line with the other.

4. In typewriting machines, the combination with the main and supplemental carriages, releasable devices normally connecting said carriages to shift together, a series 20 of adjustable column-stops mounted on the supplemental carriage, dogging means for said stops mounted on the machine frame and finger-key mechanism for releasing said connecting devices and for projecting said 25 dogging means in line with said column-stops.

5. In typewriting machines, the combination with the main and supplemental carriages, of a rack on one of said carriages, a 30 dog on the other of said carriages engaging said rack, means for disengaging said dog and rack to release said supplemental carriage and tabulating mechanism coöperating with said supplemental carriage to arrest 35 its run when released.

6. In typewriting machines, the combination with the main and supplemental carriages releasably connected for simultaneous shift, of propelling means connected to said 40 supplemental carriage, escapement mechanism coöperating with said main carriage, tabulating mechanism coöperating with said supplemental carriage to arrest its run when released from said main carriage and finger- 45 key mechanism for operating said tabulating mechanism and for effecting the release of said supplemental carriage.

7. In typewriting machines, the combination with the main carriage, of a supplemental carriage having paper-holding means mounted to slide on said main carriage, releasable devices connecting said carriages and tabulating mechanism coöperating with said supplemental carriage to arrest its run 55 when released from said main carriage.

8. In typewriting machines, the combination with the machine frame, of a main carriage mounted thereon, a supplemental carriage having paper-holding means mounted 60 on said main carriage, releasable devices connecting said carriages, propelling means connected to said supplemental carriage, escapement mechanism coöperating with said main carriage, means for releasing said supplemental carriage and tabulating mechanism 65

for arresting the run of said supplemental carriage when released.

9. In typewriting machines, the combination with the machine frame, of a main carriage mounted thereon, a supplemental carriage mounted on said main carriage and having paper-holding means, propelling means connected to said supplemental carriage, escapement mechanism coöperating with said main carriage, a rack on one of said 70 carriages, a dog on the other carriage engaging said rack, means for disengaging said dog and rack to release said supplemental carriage, and tabulating mechanism for arresting the run of said supplemental carriage 75 when released.

10. In typewriting machines, the combination with the machine frame, of a main carriage mounted on the frame, a supplemental carriage having paper-holding means 80 mounted on the main carriage, a rack on one of said carriages, a dog on the other carriage normally engaging said rack, means for disengaging said dog and rack to release said carriage, tabulating mechanism for arresting 85 the run of said supplemental carriage when released and finger-key mechanism for operating said tabulating mechanism and said releasing means.

11. In typewriting machines, the combination with the machine frame, of a main carriage mounted on the frame, a supplemental carriage having paper-holding means 90 mounted on the main carriage, propelling means connected to said supplemental carriage, escapement mechanism coöperating 95 with said main carriage, a rack on one of said carriages, a dog on the other carriage normally engaging said rack, means for disengaging said dog and rack to release said supplemental carriage and tabulating mechanism comprising a series of column-stops and 100 dogging means for said stops for arresting the run of said carriage when released.

12. In typewriting machines, the combination with the machine frame, of a main carriage mounted on the frame, a supplemental carriage having paper-holding means 105 mounted on the main carriage, propelling means connected to said supplemental carriage, escapement mechanism coöperating with said main carriage, a rack on one of said carriages, a dog on the other carriage normally engaging said rack, means for disengaging said dog and rack to release said supplemental carriage, tabulating mechanism for arresting the run of said supplemental carriage when released comprising a series of 110 column-stops adjustably mounted on the supplemental carriage, dogging means therefor mounted on the machine frame and key mechanism for operating said dogging means 115 and said releasing means.

13. In typewriting machines, the combination with the machine frame, of a main 120

- carriage mounted thereon, a supplemental carriage mounted to slide on said main carriage, a paper platen on said supplemental carriage, propelling means connected to said supplemental carriage, escapement mechanism coöperating with said main carriage, a dog on one of said carriages, a rack on the other of said carriages normally engaging said dog but shiftable out of engagement therewith, a series of adjustable column-stops mounted on said supplemental carriage and dogging means for said stops mounted on the machine frame, said dogging means having an abutment for engaging and shifting said rack to release said supplemental carriage. 14. In typewriting machines, the combination with the machine frame, of a main carriage mounted thereon, a supplemental carriage having a paper platen mounted to slide on said main carriage, propelling means connected to said supplemental carriage, escapement mechanism coöperating with said main carriage, a rack on one of said carriages, a spring-held dog on the other carriage normally engaging said rack, a shiftable abutment for releasing said dog and rack to permit the free run of said supplemental carriage and tabulating mechanism comprising a series of adjustable column-stops and a stop dog for arresting the run of said supplemental carriage when released. 15. In typewriting machines, the combination with the machine frame, a main carriage mounted on the frame, a supplemental carriage mounted to slide on said main carriage, a paper platen on said supplemental carriage, propelling means connected to said supplemental carriage, escapement mechanism coöperating with said main carriage, a pivoted rack on one of said carriages, a spring-held dog on the other of said carriages normally engaging said rack, a key-controlled member mounted on the machine frame for shifting said rack out of engagement with said dog, a series of adjustable column stops mounted on the supplemental carriage and a coöperating stop dog mounted on said key-controlled member. 16. In typewriting machines, the combination with the machine frame, of a main carriage mounted on the machine frame, a supplemental carriage, separate propelling devices for said carriages, releasable means normally connecting said carriages and tabulating mechanism coöperating with said supplemental carriage to arrest its run when released. 17. In typewriting machines, the combination with the machine frame, of a main carriage mounted thereon, a supplemental carriage having a paper platen mounted to slide on said main carriage, separate propelling devices connected to said carriages and escapement mechanism coöperating with said main carriage, a rack on one of said carriages, a dog on the other of said carriages normally engaging said rack, means for disengaging said dog and rack to permit the free run of said supplemental carriage and tabulating mechanism comprising a series of column-stops and dogging means therefor for arresting the run of said supplemental carriage when released. 18. In typewriting machines, the combination with the machine frame, of a main carriage mounted thereon, a supplemental carriage having a paper platen mounted to slide on said main carriage, propelling devices connected to said supplemental carriage, escapement mechanism coöperating with said main carriage, devices releasably connecting said carriages, means for releasing said devices to permit the free run of said supplemental carriage, tabulating mechanism comprising a series of column-stops, a coöperating stop-dog for arresting the run of said supplemental carriage when released and pawl and rack mechanism for preventing the rebound of said supplemental carriage when one of said column-stops is brought into engagement with said stop-dog. 19. A typewriting machine comprising a paper-carrying device, propelling means therefor, a series of type and a series of keys, a letter-spacing escapement for said carriage associated with and operated by said keys, a tabulating mechanism for arresting the run of the carriage comprising a series of stops, a tabulating release independent of said letter-spacing escapement and means for actuating said tabulating release. 20. A type-writing machine comprising a paper-carrying device, propelling means therefor, a series of type and a series of keys, a letter-spacing escapement associated with and operatively connected thereto, a tabulating release for said carriage, a key operatively connected thereto, said release and key actuating said paper-carrying device independently of said letter-spacing escapement. 21. In a typewriting machine, the combination with the carriage, of mechanism for arresting the run of the carriage comprising coöperating stop members, one of said stop members being shiftable into and out of line with the other and means for preventing rebound of the carriage comprising two coöperating parts separate from said stop members, one of which is shiftable into and out of engagement with the other, said shiftable part being connected to said shiftable stop member and moved into engagement with the other of said parts when said shiftable stop member is moved into line with the other stop member. 22. In typewriting machines, the com-

bination with the carriage, of means for arresting the run of the carriage comprising coöperating stop members, one of which is movable into and out of line with the other 5 and means for checking the rebound of the carriage when said stop members are brought into engagement comprising coöperating pawl and rack members, one of which members is connected to and shifted with said 10 movable stop member as the latter is moved into line with the other of said stop members.

23. In typewriting machines the combination with the carriage, of means for arresting the run of the carriage comprising coöperating stop members, one of which is movable into and out of line with the other and means for preventing rebound of the carriage when said stop members are brought 15 into engagement comprising normally disengaged pawl and rack members, one of which is mounted on the carriage and one of which is mounted on and moved with said shiftable stop member as the latter is shifted 20 into line with the other of said stop members.

24. In typewriting machines, the combination with the frame and carriage mounted thereon, of a stop mounted on the carriage, a coöperating stop shiftably mounted 30 on the frame to move into and out of line with said carriage stop, a rebound preventing device mounted on and movable with said shiftable stop, a longitudinally extending member on the carriage separate from 35 the stop thereon with which said device engages.

25. In typewriting machines, the combination with the carriage, of a series of column stops mounted thereon, a shiftable 40 stop dog coöperating with said column stop, a rack on the carriage and a pawl connected to and shifted with said stop dog into and out of engagement with said rack to prevent the rebound of said carriage.

45 26. In typewriting machines, the combination with the carriage, of means for arresting the run of the carriage comprising coöperating stop members, one of which is shiftable into and out of line with the other 50 and means for preventing rebound of said carriage when said stop members are brought into engagement comprising a rack and a spring-held pawl movable into and out of engagement with said rack and a tabulating 55 key for shifting said movable stop member and said pawl.

27. In typewriting machines, the combination with the carriage, of a series of column stops mounted thereon, a stop dog movable 60 into and out of line with said column stops, a rack on the carriage and a spring-held pawl connected to said stop dog and moved there- with into and out of engagement with said rack to prevent rebound of the carriage when

one of said column stops engages said stop 65 dog.

28. In typewriting machines, the combination with the carriage, of means for arresting the run of the carriage comprising coöperating stop members, one of which is shiftable into and out of line with the other of said members and means for preventing the rebound of the carriage when said stop members are brought into engagement comprising a rack having a series of teeth corresponding 75 with the different letter space positions of the carriage and a pawl for engaging said rack, one of said pawl and rack members being shiftable into and out of engagement with the other, and a tabulating key 80 for operating said shiftable stop member and for bringing said pawl and rack members into engagement.

29. In typewriting machines, the combination with the carriage, of means for arresting the run of the carriage comprising coöperating stop members, one of which is shiftable into and out of line with the other, a tabulating key for operating said shiftable 85 stop member and means for preventing rebound of the carriage when said stop members are brought into engagement comprising a rack and a coöperating pawl for engaging the teeth of said rack, said pawl and rack members being normally disengaged and one 90 of said members being connected to said tabulating key and arranged to be shifted thereby into engagement with the other of said members.

30. In a typewriting machine, the combination with the carriage mechanism, a propelling means therefor, a letter space escapement coöperating with said carriage mechanism, a tabulating release for said carriage mechanism independent of said escapement 100 and stop devices for arresting the run of said carriage mechanism.

31. In typewriting machines, the combination with the carriage mechanism, a series of type and a series of type-operating keys, 110 of a letter space escapement coöperating with said carriage mechanism and actuated by said type-operating keys, a tabulating release for said carriage mechanism independent of said escapement, stop devices for said carriage mechanism and a tabulating key 115 connected to operate said tabulating escapement and said stop devices.

32. In typewriting machines, the combination with the main and supplemental car- 120 riages, of a letter space escapement coöperating with one of said carriages, independently operable tabulating releasing devices coöperating with the other of said carriages and stop devices for arresting the run of the 125 latter carriage.

33. In typewriting machines, the combination with the main and supplemental car-

riages, a series of type and a series of type-operating keys, of a letter space escapement actuated by said type-operating keys and coöperating with one of said carriages, independently operable tabulating releasing devices coöperating with the other of said carriages, stop devices for arresting the run of

the latter carriage and a tabulating key for operating said tabulating escapement and said stop devices.
